United States Patent

Des. 239,394
Patented Mar. 30, 1976

239,394

BUTTON CONTROL UNIT

Gerald M. Adams, Fayetteville, and James H. Frakes, Jr.,
Manlius, N.Y., assignors to SCM Corporation, New
York, N.Y.

Filed July 29, 1974, Ser. No. 492,622

Term of patent 14 years

Int. Cl. D13—03
U.S. Cl. D26—13 R

FIG. 1 is a perspective view of a button control unit showing our new design;

FIG. 2 is a top plan view thereof; and

FIG. 3 is a side elevational view thereof.

We claim:

The ornamental design for a button control unit, as shown.
